UNITED STATES PATENT OFFICE

140,757

DESIGN FOR A PHOTOGRAPHIC VIEWING AND PRINTING CABINET

Horace Warman, London, England, assignor to
Pictorial Machinery Limited, London, England,
a British company

Application August 18, 1944, Serial No. 114,935

In Great Britain April 6, 1944

Term of patent 7 years

(Cl. D61—1)

To all whom it may concern:

Be it known that I, Horace Warman, a subject of the King of England, residing at 9 Greenway, Totteridge, London, N. 20, England, have invented a new, original, and ornamental Design for a Photographic Viewing and Printing Cabinet, of which the following is a specification, reference being had to the accompanying drawing, forming part thereof.

Figure 1 is a front perspective view of a photographic viewing and printing cabinet showing my new design, and

Figure 2 is a rear perspective view of the cabinet.

I claim:

The ornamental design for a photographic viewing and printing cabinet, as shown.

HORACE WARMAN.
